FIRING PIN

Roy A. Wykoff, Jr., Keokuk, Iowa

Application October 1, 1946, Serial No. 700,542

7 Claims. (Cl. 42—69)

(Granted under the act of March 3, 1883, as
amended April 30, 1928; 370 O. G. 757)

1

The invention described herein may be manufactured and used by or for the Government for governmental purposes, without the payment to me of any royalty thereon:

The invention relates to firing pins for use in gun actions having reciprocating breech closing bolts and a firing pin reciprocably mounted in the bolt. It is particularly useful in the Browning machine gun as now used in the U. S. Army, illustrations of which may be found in the patents to Browning, 1,293,022; 1,628,226; and others.

In these guns great difficulty has been experienced because of the breakage of firing pin points, and it has been a practice to carry a number of spare parts including one or more spare firing pins, the firing pins being quickly attached to a firing pin extension which is mounted in the bolt and is itself detachable from the bolt.

These guns are embodied in readily portable form to a large extent, and incident to field service, particularly in jungle warfare, it is desirable to reduce impedimenta, because spare parts have become lost and failures of firing pins have resulted in many instances in putting guns out of action permanently because of lack of a replacement firing pin. It is therefore an important aim of this invention to minimize the need for carrying spare firing pins, enabling the production of a reversible firing pin which may be readily installed in a firing pin extension approximately in the same way as in the present firing pin extension, excepting that a slight enlargement of the latter is involved.

It has heretofore been recognized as desirable to utilize a reversible firing pin, but retaining the advantages of quick removal and replacement and maintenance of the correct tolerances and weights in the parts have presented a difficulty which was not overcome. It is therefore an important aim of the present invention to present a pin which corresponds very closely to the pin in current use and which may be quickly removed and reversed or replaced by men in the field, principally by manual operations.

A further aim is to present a firing pin assembly which will preserve the rugged characteristics necessary in a gun action which is subjected to the severe use and some abuse in the field.

It is also an aim to minimize the number of parts required and to preserve the simplicity of machining and manual assembly and replacement operations involved in the improved device.

Additional objects, advantages and features of

2

invention reside in the construction, arrangement and combination of parts involved in the embodiment of the invention, as will be apparent or understood from the following description and accompanying drawings, wherein:

Figure 1 is a longitudinal sectional view of the bolt and a portion of the barrel extension of a current model of Browning machine gun of .50 cal. as used in the U. S. Army;

Figure 2 is a fragmentary top view of the firing pin extension and a part of the firing pin body engaged therein;

Figure 3 is a front end elevation of the firing pin extension;

Figure 4 is a section of the firing pin and firing pin extension, on the line 4—4 of Figure 1;

Figure 5 is a fragmentary top view of middle parts of the firing pin body;

Figure 6 is an end view of a firing pin body in position for insertion in the firing pin extension of Figure 3;

Figure 7 is a fragmentary vertical longitudinal sectional view of the forward part of a firing pin extension modified, and a modification of the firing pin body for use therewith;

Figure 8 is a similar view showing means for holding the firing pin body against rotation in the firing pin extension;

Figure 9 is a view of the firing pin body from the right of Figure 8;

Referring more particularly to the drawings, there is illustrated approximately full size, the bolt 10 of the Browning gun mentioned, in battery relation to the barrel 11, the latter being fixed in the barrel extension 12 as heretofore, and at this battery position of the parts, a bolt lock 13 (Figure 1) locks the bolt to the barrel extension. A sear 14 is shown mounted as usual at the rear end of the bolt, and a cocking lever 15 also, having the usual structure and function with the firing pin extension; the rear part of which is identical with the prior device excepting for a slight increase in diameter.

The foregoing named parts of the structure are well understood and their functions remain unchanged, in consequence of which they will not be described in greater detail.

The firing pin assembly in the present instance comprises a tubular firing pin extension 16 which is practically identical in form to the prior replaced element with the exception of the formation of the forward end thereof. This extension is engaged in a longitudinal main bore 17 in the bolt, somewhat larger in diameter than the bore for the prior firing pin extension, the result be-

ing that the increased weight in my improved device is compensated for by removal of material in the bolt as far as mass in the bolt is concerned. The firing pin extension has at the rear the usual vertical longitudinal diametrical slot 18 receiving therein a slideable sear stop pin 19 by which the pin extension is held against rotation in the bolt. This pin also serves as a seat for the firing pin spring 20, which is somewhat larger in diameter than the prior spring, the firing pin extension being correctly bored to permit free action of this spring therein. The larger spring has an interior diameter which is adapted to receive freely therein a rearwardly directed firing pin of the same diameter as the prior firing pin, as will be described. Contrary to prior practice, instead of a single seat pin heretofore set across the forward end of the firing pin extension as a seat for the forward end of the spring, two pins 21 are set across the firing pin extension a distance short of its forward end, the pins being spaced apart a distance slightly more than the diameter of the principal shank portion of the conventional firing pin. The firing pin extension in this instance is also slightly longer than the prior displaced element.

A firing pin body 22 is shown (Figures 1, 4, 5 and 6), having identical end portions 29 joined by a somewhat thickened middle shank 23 centrally of which a circular stop flange 24 is formed integrally thereon corresponding to a similar flange heretofore used on the conventional firing pin and of a diameter slightly less than the diameter of the main bore 17. The forward end of the extension 16 and the two main faces of the flange 24 are planiform and normal to the axis of the bore 17. Spaced from the flange 24 there are integrally formed on the middle shank 23 collars 25 each comprising a semicircular part 26 of relatively large diameter and a second semicircular part 27 of less diameter than part 26. Flats 28 are formed on parts 27, as clearly shown at Figures 5 and 6. End portions 29 which may be circular in cross section or substantially rectangular as has been a more recent practice extend from collars 25. Each end portion 29 has at its outer part a reduced cylindrical shank 30 and cylindrical firing pin point 31 of conventional size and form for engagement through the pressure plate 32 at the forward end of the bolt. Points 33 project beyond plate 32 when the firing pin assembly is at the forward limit of its movement in the bolt. The bolt has a reduced forward bore 33 adapted to receive the firing pin proper slidably therein, this bore being enlarged around the part 30 of the firing pin and reduced adjacent the face of the bolt to fit snugly around the firing pin point 31 as heretofore. Limitation of movement of the firing pin is effected as heretofore by extending bore 17 forwardly so that when the firing pin assembly is engaged in the bore and the sear depressed, the forward collar 25 will engage the forward end of the bore and limit the forward motion of the pin with its point projected into the T-slot 34 of the bolt.

A circular channel 35 is cut in the interior of pin extension 16 a distance rearwardly from its forward end 16 a distance equal to the spacing between the flange 24 and one of the collars 25. Forwardly of this channel, the upper half of the pin extension 16 is cut away to an equal radius to form a semicircular entrance channel 36 flush with the bottom of the channel 35, the radius of the channels 35 and 36 is slightly greater than the radius of the semicircular lower part 26 of

the collar 25. A semicircular retaining flange 39 is thus formed in the firing pin extension forwardly of channel 35.

A leaf spring 37 is set in a longitudinal slot 38 formed through the wall of the pin extension, the spring being shaped so as to press downwardly and engage upon the flat 28 of collar 25 when properly positioned in the firing pin extension as will be obvious from inspection of Figure 1. The forward extremity of the spring 37 is bent radially outwardly to permit one of the collars 25 to cam it outwardly when the firing pin is pressed longitudinally into the pin extension with the part 26 uppermost.

By the formation of the parts as described, it will be seen that assembly of the pin 22 with extension 16 may be effected by sliding movement of pin 22 into the forward end of the firing pin extension, the spring 37 being cammed outwardly by portion 26, Figure 6. When the rearward collar 25 has entered sufficiently to align with the channel 35, the firing pin body is then rotated 180° so as to bring the semicircular part 26 into the channel part 35 behind flange 39 so that flat 28 is engaged by spring 37. Accidental rotation of the firing pin 22 from proper locked position relatively to extension 16 and its escape from the firing pin extension are thereby prevented.

If desired, a bevel 26' may be formed as clearly shown at Figure 6, to facilitate passage of the collar past the tongue of the spring 37.

The firing pin assembly comprising body 22 and extension 16, may then be introduced into the bolt in conventional manner and the sear stop pin cocking lever and other parts replaced as heretofore.

It is apparent that either end of the firing pin body may be extended forwardly from the firing pin extension without changing the function of the pin and that a quick manual removal and manual replacement of the firing pin body in the firing pin extension is made possible with a minimum of effort.

In Figure 7 there is illustrated a modification of the invention in which the forward part of the firing pin extension 16' is a simple tubular part with a flush planiform forward end, its bore being slightly enlarged and interiorly threaded. The firing pin body in this case has identical end portions as before, but in place of each collar 25, an exteriorly threaded concentric boss 40 is integrally formed at the base of each firing pin proper 29'. Between and joining the bosses 40, the flange 24' is formed, corresponding to the flange 24, and the length of the firing pin body from the flange 24' to the extremity of each point portion should be approximately the same as the distance between flange 24 and point 31 in the first described device. The main bore 17' in the bolt in this instance is somewhat shorter than the bore 17, and is counterbored forwardly as at 41 to accommodate with clearance the forwardly located boss 40 of the device, and the shoulder 42 thus provided should engage the flange 24' when the firing pin has its point in firing position as in Figure 1.

The introduction and removal of the firing pin body 22' of Figure 7 will be readily understood without detailed disclosure, it being possible to screw either of the bosses 40 into the end of the firing pin extension 16'. Two cross pins 21' are engaged across the firing pin extension, as a seat for the firing pin spring. These pins act to confine the adjacent end of the firing pin spring 75 within the bore in extension 16' when body 22'

is unscrewed from the extension and thus prevent the possibility of its loss.

In Figures 8 and 9 the construction is the same as in Figure 7, but the flange 24a corresponding to the flange 24' is peripherally notched as at 42' so that the firing pin may be readily rotated by a tool engaged in one or more of the notches, and on the end of the firing pin extension spring pressed means is provided, arranged to engage in one or more of the notches as the firing pin is screwed into place, and so yieldingly hold the firing pin against rotation in the firing pin extension. In the present instance the spring device comprises a simple bullet latch 43, although other equivalent devices suitable for the purpose may be substituted as discretion may dictate.

While I have disclosed the invention with particularity in its best form known to me, it will nevertheless be understood that this is purely exemplary and that changes in construction, substitution of materials and equivalents, mechanical or otherwise, may be made without departing from the spirit of the invention set forth in the appended claims.

I claim:

1. An elongated firing pin terminating at one end in a firing pin point, said pin having, remote from said point, a radial flange comprising two coplanar semi-circular portions of different radii.

2. An elongated firing pin of uniform cross-section tapering to a point at one end, said pin having first and second axially spaced flanges remote from said point, said first flange comprising two coplanar semi-circular portions of different radii, said second flange being circular and of a radius greater than said first two radii.

3. A firing pin as recited in claim 2, said first flange having its semi-circular portion of smaller radius bounded by a chord at right angles to the center radius of said portion.

4. In a firing pin assembly, a tubular firing pin extension having an internal peripheral channel spaced a predetermined distance from one end thereof, the flange thus formed between said

channel and said one end being removed throughout 180° of arc, a firing pin tapering to a point at one end and having a first radial flange remote from said one end, said flange comprising two semi-circular portions of different radii, one said portion having a radius equal to the internal radius of said extension, the other said portion having a radius equal to that of said channel, whereby said extension and pin may be united by axially inserting said pin into the channeled end of said extension, followed by a 180° relative rotation of said pin and extension from a first to a second position.

5. An assembly as recited in claim 4, said firing pin having a point at each end, said radial flange being midway between said ends, whereby when said pin and extension are assembled, one half of said pin is housed within said assembly.

6. An assembly as recited in claim 4, said pin having a second radial flange spaced axially from said first flange and constructed and arranged to abut the adjacent end of said extension when said pin and extension are assembled.

7. An assembly as recited in claim 4, said semi-circular flange portion of smaller radius being truncated along a chord thereof and spring means carried by said extension and adapted to engage said truncated portion to yieldingly maintain said pin in said second position of rotational adjustment relatively to said extension.

ROY A. WYKOFF, JR.
